UNITED STATES PATENT OFFICE.

JOHN A. ABEL AND EDWARD C. ABEL, OF WOODHAVEN, NEW YORK.

ARTICLE OF JEWELRY.

1,146,543:

Specification of Letters Patent. Patented July 13, 1915.

Application filed July 31, 1914. Serial No. 854,268.

To all whom it may concern:

Be it known that we, JOHN A. ABEL and EDWARD C. ABEL, citizens of the United States of America, residing at Woodhaven, in the county of Queens and State of New York, have invented certain new and useful Improvements in Articles of Jewelry, of which the following is a specification.

This invention relates to articles of jewelry and aims to provide certain improvements therein.

The invention has particular reference to rings, but is also applicable to crescents, bar pins, brooches, lavallières, scarf pins, bracelets, etc. In such articles it is common to use a large number of precious stones so that the mounting is practically filled with them, and in the ordinary construction the recesses in which the stones are set extend through the mounting, so that they are open at the back. In such construction unless each mounting is raised the light does not adequately reach the backs of the stones and there is usually left no inner surface for the engraving of names, dates, marks, numbers, trade-marks, or the like. This is particularly true with certain types of wedding rings which are set completely around the ring with small diamonds or other precious stones. According to the present invention we obviate these difficulties by providing a mounting bar in which the stones are set, and a base bar which is ordinarily imperforated and which is spaced apart from the mounting bar with the effect that the latter is elevated above it so that the light reaches the backs of the stones. Preferably at intervals between the two are spacing portions or connections which are preferably sufficiently small size to leave large openings between the two bars. The base bar provides an adequate surface for engraving or the like, and in addition presents a smooth surface to the finger, which is adapted to withstand wear. In the case of rings, the bands preferably each comprise a complete ring, the outer ring forming the mounting bar and the inner ring the base bar.

Referring to the drawings which illustrate the invention as applied to a ring, Figure 1 is a side view of the ring; Fig. 2 is a sectional view on the line 2-2 in Fig. 1. Fig. 3 is an enlarged side elevation of a portion of the ring. Fig. 4 is a sectional view

taken circumferentially, and Fig. 5 is a cross-section on the line 5-5 in Fig. 4.

In the drawings, let A indicate the mounting bar which is preferably in the form of a complete ring and which is provided with recesses B designed for the reception of the stone C. The latter may be set in place by means of prongs D, or by turning over the metal upon the stones, or in any other suitable way.

E indicates the base bar which is also preferably of circular form, and which is best formed with a flat and smooth inner surface designed to receive the engraving. The two bars are spaced apart so as to provide openings or spaces G, preferably of considerable size, through which the light may pass to the backs of the stones, thus increasing their brilliancy. Spaces G are also desirable for cleaning purposes, as they permit access to the rear faces of the stones. In the drawing, the connections are indicated by the letter F, and consist of small ring-shaped members soldered to both bars. Any other suitable means may be employed for this purpose, as they may be formed integrally with one of the bars if desired.

In the case of crescents, bar pins, brooches, bracelets, scarf pins, and other styles or shapes that may be produced, the rear bar will be given the shape suitable for the particular design in view to conform to the shape of the design of mounting.

While we have shown and described one form of the invention, it is understood that we do not wish to be limited thereto, since various changes may be made therein without departing from the spirit of the invention.

What we claim is:—

1. An article of jewelry having a mounting bar and a base bar spaced apart the one from the other, the mounting bar having a plurality of openings passing completely through it, said openings adapted to carry stones with the backs of the stones accessible through the space between said bars.

2. An article of jewelry having a mounting bar and a base bar spaced apart the one from the other, the mounting bar having a recess extending through it and a stone in said recess, the back of the stone being accessible through the space between said bars.

3. An article of jewelry having an inner

plane surface and an apertured outer surface, there being a space between said surfaces, and a series of stones mounted in said apertures, the backs of said stones being accessible through said space.

5 4. An article of jewelry having a mounting bar carrying a series of stones, and a base bar connected to and beneath said mounting bar and having an imperforate inner surface.

10 5. A ring comprising an inner band and an outer band, connected to and spaced apart the one from the other, the outer band having a series of stones.

15 6. A ring comprising an inner band and an outer band, the outer band having a series of recesses, and having stones set therein, said outer band and inner band being connected and being spaced apart.

20 7. A ring comprising an inner band and an outer band, spaced apart the one from

the other, the outer band having a series of stones, and means for spacing said bands apart, said means being spaced apart circumferentially to leave openings to the 25 space between said bands.

8. A ring comprising an outer band A and inner band E, the inner band being substantially imperforate and the outer band having apertures passing through it and 30 stones in said apertures, and a series of connections between said bands, said connections being spaced apart circumferentially of the ring to leave openings between them.

In witness whereof, we have hereunto 35 signed our names in the presence of two subscribing witnesses.

JOHN A. ABEL.
EDWARD C. ABEL.
